E. E. HILER

CHOKE COIL AMPLIFICATION UNIT

Filed April 30, 1926

INVENTOR.
Edward E. Hiler:

BY
Fraunfeld and Richards,
ATTORNEYS.

UNITED STATES PATENT OFFICE.

EDWARD E. HILER, OF BLOOMFIELD, NEW JERSEY.

CHOKE-COIL AMPLIFICATION UNIT.

Application filed April 30, 1926. Serial No. 105,757.

This invention relates to improvements in choke-coil amplification units for use in radio signal amplifying circuits; and the invention has reference to a simplified construction and arrangement of choke-coil units of the general kind and type shown in my United States Letters Patent No. 1,589,692, dated June 22, 1926.

This invention has for its principal object 10 to provide a simplified arrangement of choke-coils and condenser in an open frame assembly suitable for quick and easy mounting or attachment directly upon a main panel, base or other permanent member of 15 a radio apparatus. The novel arrangement and assembly of the choke-coil unit contemplated by this invention is relatively inexpensive, and yet compact, durable and strong.

The present invention is clearly illustrated 20 in the accompanying drawings, in which:—

Figure 1 is a front elevation of the choke-coil unit in attached relation to a panel or other supporting structure; Figure 2 is a top plan view of the same; and Figure 3 is 25 a sectional view, taken on line 3—3 in Figure 2.

Similar characters of reference are employed in all of the aforesaid views, to indicate corresponding parts.

30 The reference character 4 indicates a laminated metallic core made of annealed carbon sheet steel substantially in the form of a figure 8 so as to provide outer lateral members 5 in properly spaced relation to an 35 intermediate lateral member 6. Mounted on one outer lateral member 5 of the core 4 is one choke coil 7; and, in like manner, mounted on the other outer lateral member 5 of the core 4 is another choke coil 8. This arrangement interposes between the choke coils 40 7 and 8 the intermediate lateral member 6 of the core 4, thus assuring a proper magnetic circuit for each coil without intervening air gap.

45 Extending through the outlying corner portions of the core 4 are supporting legs or rods 9, the respective ends of which project beyond each face of the core. The rearward ends of said legs or rods 9 are screw threaded to receive stop-nuts 10, which abut the rearward face of the core 4 and prevent displacement of the core and its coils, as assembled and supported on said legs or rods 50 9, in a rearward direction.

55 Telescopically fitted over the forward end portions of said legs or rods 9 are spacing

sleeves 11 for supporting a face plate 12 on said legs or rods 9 in outwardly spaced relation to said core and its coils. This face plate is preferably made of a suitable rigid 60 insulation material, and serves to support a plurality of binding posts or similar electrical terminal contact means, for purposes subsequently described.

In practice the legs or rods 9 are preferably provided at their outer ends with heads 13, which abut against the outer face of the face plate 12 and thus retain the latter against outward displacement from the said legs or rods.

Disposed between the face plate 12 and the choke-coils 7 and 8, so as to lie intermediate the sleeves 11 on the legs or rods 9 at the respective outer ends of the core 4, is a coupling grid condenser element 14 provided 75 with terminal projections 15 and 16 respectively of opposite polarity. As thus assembled, the condenser 14 is conveniently arranged for electrical connection between the output side or plate of one amplifying vacuum tube and the grid of a succeeding amplifying vacuum tube, when the complete choke coil unit is connected in a radio receiving circuit.

Connected with and supported by said 80 face plate is a battery terminal connection or binding post B, a filament terminal connection or binding post F, a plate terminal connection or binding post P, and a grid terminal connection or binding post G, each 90 respectively provided at their inner ends, beneath the face plate 12, with terminal lugs b, f, p and g. To the terminal lug b is connected one end 7' of the choke-coil 7, the 95 opposite end 7" of which is connected with the terminal projection 15 of the condenser 14, and thence through a wire connection 17 is connected with the terminal lug p, thus connecting both the condenser 14 and choke-coil 7 on the plate side of a stage in an 100 amplifying circuit. To the terminal lug f is connected one end 8' of the choke-coil 8, the opposite end 8" of which is connected with the terminal projection 16 of the condenser 14, and thence through a wire connection 18 105 is connected with the terminal lug g, thus connecting both the condenser 14 and choke-coil 8 on the grid side of a stage in an amplifying circuit.

Interposed between the condenser 14 and 110 the inner ends of the terminal connections or binding posts of the face plate 12 is a

shield plate 19 made of a suitable insulation material.

- In the choke-coil unit, as thus constructed and assembled, the rearward free ends of the legs or rods 9 project or extend freely beyond the rearward side of the choke-coils 7 and 8, consequently when it is desired to mount the unit upon a main panel, base or other fixed member of a radio apparatus, 10 as e. g. the panel 19, the free ends of said legs or rods 9 are projected through holes in said panel, spaced to correspond to the positions of said legs or rods 9, until the choke-coils 7 and 8 abut against the panel 15 surface. Fastening nuts 20 are thereupon applied on the projecting portions of the legs or rods 9 to abut against the opposite surface of the panel 19, thus firmly securing the unit in mounted and supported relation 20 to the panel.
- From the above description it will be apparent that a very simple and inexpensive form of choke-coil unit is provided, which may be quickly, easily and firmly 25 secured in operative relation to a radio apparatus; and at the same time the parts of the unit are compactly and strongly assembled, and have been reduced to a minimum in weight.
- 30 It will be understood that although the above description sets forth one satisfactory form of unit assembly and arrangement, various modifications and detail changes may be made in such assembly and arrangement within the scope of the claims hereunto appended. Hence, I do not limit myself to the exact arrangement and construction of the parts as above described nor do I limit myself to the exact details of the 35 construction thereof as illustrated in the accompanying drawings.

I claim:—

1. A unitary device of the kind described, comprising a laminate metallic core substantially in the form of a figure 8, a pair of choke-coils mounted respectively on the outer lateral members of said core with the intermediate lateral member of the latter disposed therebetween, a face-plate, rods extending through said core and face-plate to connect the same in assembled relation, means for retaining said core and face-plate against displacement from said rods with the latter in spaced relation from the former, 45 and external circuit connections carried by 50 55

said face-plate between certain of which said choke-coils are electrically connected.

2. A unitary device of the kind described, comprising a laminate core substantially in the form of a figure 8, a pair of choke-coils 60 mounted respectively on the outer lateral members of said core with the intermediate lateral member of the latter disposed between said choke-coils, supporting rods extending through the corner portions of said core, the rearward ends of said rods being threaded, stop nuts on said threaded ends to abut said core and position the same on said rods, a face plate supported on the forward ends of said rods, spacing sleeves on 65 said rods intermediate said face plate and core, external circuit connection carried by said face plate between certain of which said choke-coils are electrically connected, the rearward free ends of said rods being 70 adapted for extension through a support, a fastening means for retaining said rods in 75 connected relation to said support.

3. A unitary device of the kind described, comprising a laminate core substantially in 80 the form of a figure 8, a pair of choke-coils mounted respectively on the outer lateral members of said core with the intermediate lateral member of the latter disposed between said choke-coils, supporting rods extending through the corner portions of said core, the rearward ends of said rods being threaded, stop nuts on said threaded ends to abut said core and position the same on 85 said rods, a face plate supported on the forward ends of said rods, spacing sleeves on 90 said rods intermediate said face plate and core, external circuit connections carried by said face plate between certain of which said choke-coils are electrically connected, a 95 condenser element disposed intermediate said choke-coils and said face plate and retained against sidewise displacement by said rod enclosing spacing sleeves, said condenser being electrically connected between certain 100 of said circuit connections carried by said face plate, the rearward free ends of said rods being adapted for extension through a support, and fastening means for retaining 105 said rods in connected relation to said support.

In testimony, that I claim the invention set forth above I have hereunto set my hand this 24th day of April, 1926.

EDWARD E. HILER.
